Primary Examiner — Mary Ann Calabrese*Assistant Examiner* — Catherine Ho(74) *Attorney, Agent, or Firm* — Banner & Witcoff, Ltd.(57) **CLAIM**

The ornamental design for a rack for furniture, as shown and described.

DESCRIPTION

FIG. 1 is a perspective view of a rack for furniture showing my new design;

FIG. 2 is a front view thereof;

FIG. 3 is a rear view thereof;

FIG. 4 is a right side view thereof, the left side view thereof being a mirror image;

FIG. 5 is a top view thereof;

FIG. 6 is a bottom view thereof;

FIG. 7 is a perspective view of usage; and,

FIG. 8 is a perspective view of usage.

The rack for furniture is made from a flexible material.

The broken lines in FIGS. 1-6 are for the purpose of illustrating portions of the rack of the furniture and form no part of the claimed design. The broken lines in FIGS. 7-8 are for the purpose of illustrating the environmental structure and form no part of the claimed design.

1 Claim, 8 Drawing Sheets(56)
